(No Model.)

W. KENDALL.

PORTABLE BATH.

No. 283,117.

Patented Aug. 14, 1883.

N. PETERS, Photo-Lithographer, Washington, D. C.

UNITED STATES PATENT OFFICE.

WILLIAM KENDALL, OF LOGANSPORT, INDIANA.

PORABLE BATH.

SPECIFICATION forming part of Letters Patent No. 283,117, dated August 14, 1883.

Application filed December 19, 1882. (No model.)

To all whom it may concern:

Be it known that I, WILLIAM KENDALL, of Logansport, Cass. county, Indiana, have invented new and useful Improvements in Portable Baths, of which the following is a specification.

My invention relates to improvements in those portable bathing apparatus which, in association with a suitable tub, possess a reservoir or water-holder capable of elevation to any desired height above the tub by means of a cord and windlass, so as to be available for use as a shower-bath; and my present devices are especially designed as improvements on the subject-matter of my Patent No. 250,926, granted December 13, 1881, in which a shower-bath apparatus is made available for use with a common "hip" or other bath-tub, with which it firmly connects when in condition for use, and from which it is quickly and easily detached for separate use of either tub or shower apparatus, or both, and by which the component members of the shower apparatus are easily separated from one another for compact stowage or transportation.

In the accompanying drawings, Figure 1 is a perspective view of a bathing apparatus embodying my improvements. Fig. 2 is a detached representation of my base and the lower portion of my gallows-frame. Fig. 3 is a perspective view of my preferred form of tub, from which a portion is broken away to exhibit the mode of construction. Fig. 4 is a vertical section of a portion of the tub. Figs. 5 and 6 are respectively a perspective view and vertical section of my preferred form of two-way cock or faucet.

A represents a bed or base, preferably of wood, the same being a rectangular or trapezoidal open frame, composed of two parallel bottom strips, $a a$, crossed by two upper strips, $a' a'$, at a sufficient distance from the ends of $a a$ to leave projecting portions $a'' a''$. Pivoted to the portions $a' a'$, near their extremities, are buttons B B B B.

My gallows-frame consists of two feet, C C, which have gains c on their under sides, at their ends, to fit over and rest upon the projecting ends $a'' a''$ of the strips $a a$, in the man-

ner shown in Fig. 1, where they are retained 50 by the buttons B B B B.

Rising from middle of feet C C are the posts D D of my gallows-frame, which, with its reservoir H and suspending-windlass G, may be substantially of the construction described 55 in my aforesaid patent, to which reference may be made for more specific description of these parts.

The cup or barrel N of my faucet is now preferably formed with a notch, n, through 60 which projects a handle, o, from the spigot O, and whose vertical ends limit and guide the sweep of the handle to the fully-open and the fully-closed condition of the cock.

My preferred construction of tub V is as 65 follows: The body E is formed of galvanized iron or other suitable sheet metal, with the represented downward taper and oblong transverse section, and with its lower edges bent horizontally inward to form flanges e. The 70 bottom is formed of a slab, F, of wood, of shape corresponding to the lower transverse section of the body, and of just so much less dimensions as, when incased in the sheet-metal lining R, to snugly fit the lower portion of the 75 body and rest upon the flange e, as shown in Figs. 3 and 4. The joint x, between the edge of the bottom and the body-wall, being then soldered, thus secures the parts permanently together and renders the vessel water-tight. 80 For additional security spikes S may be driven through the body into the bottom. Wooden cleats or battens T T, fastened transversely to the bottom, serve to stiffen the same, and also serve, by their engagement on the outside 85 of the base-pieces $a a$, as shown in Fig. 1, to hold the tub to its proper position upon the base.

It will be seen that my shower apparatus and my tub are capable of ready separation, 90 and that either one may be used independently of the other.

I claim as new and of my invention—

1. In a portable bathing apparatus, the stand composed of base $a a a' a' a'' a''$, buttons 95 B B B B, feet C C, and posts D D, substantially as set forth.

2. In combination with the base $a a a' a' a'' a''$,

the tub V, having the described transverse cleats T T.

3. The tub V, composed of sheet metal body E e and the composite bottom composed of wooden slab F, whose top and edges are lined with sheet metal, R, said bottom being secured in the body by solder-joint x, substantially as set forth.

In testimony of which invention I hereunto set my hand.

WILLIAM KENDALL.
